UNITED STATES PATENT OFFICE.

JAMES NICHOLAS YOUNG, OF PARMA, MICHIGAN.

WIRE-FENCE TIGHTENER.

SPECIFICATION forming part of Letters Patent No. 583,318, dated May 25, 1897.

Application filed January 27, 1897. Serial No. 620,931. (No model.)

To all whom it may concern:

Be it known that I, JAMES NICHOLAS YOUNG, a citizen of the United States, residing at Parma, in the county of Jackson and State of Michigan, have invented certain new and useful Improvements in Wire-Fence Tighteners; and I do hereby declare the following to be a full, clear, and exact description of the invention, such as will enable others skilled in the art to which it appertains to make and use the same.

My invention relates to certain new and useful improvements in wire-fence tighteners, the object being to provide a simple construction of device adapted for application to the meeting ends of the strands of a wire fence, whereby the said ends may be drawn taut and while taut connected together.

To this end my invention consists in a device of the character described comprising a shaft having two clamping-blocks adapted for application to the ends of a wire-fence strand and movable away from and toward each other, and mechanism for imparting motion to the said clamping-blocks for tightening said ends of the wire strands, whereby the same may be drawn taut and connected in an easy and convenient manner.

My invention also consists in certain novel constructions, combinations, and arrangements of parts, as will be hereinafter more fully described, and set forth in the appended claims.

In the accompanying drawings, Figure 1 is a side elevation view of my improved wire-tightening device, showing the same applied to one of the wire strands of a fence. Fig. 2 is a view looking toward the end of one of the clamping-blocks. Fig. 3 is an enlarged detail view of the screw-shaft-operating mechanism and a portion of the screw-shaft. Fig. 4 is a vertical sectional view through the same on the line xx . Fig. 5 is a view of the clamping-wedge portions of the clamping-block, showing in detail the construction of the same.

Referring to the drawings, the letter A designates the shaft, the ends b b' of which are reversely screw-threaded, one having a right-hand thread and the other a left-hand thread. The clamping-blocks B B' are arranged on each of the said ends of the screw-shaft and

are movable thereon relative to each other. Each block is provided with a fixed nut C C' , having position in a socket therein, and the said threaded ends of the screw-shaft engage these nuts and extend through the said clamping-blocks to the outer side thereof. These blocks are also provided at their lower ends with slots, whereby they are mounted upon the longitudinal flat sliding bar D, which is arranged parallel with the said screw-shaft A. A shielding-bar e e' is fitted upon the exteriorly-exposed ends of the said screw-shaft and sliding bar and serves to prevent the end of the said shaft from being bent out of shape while in use.

The mechanism for operating the screw-shaft comprises a body F, having a longitudinal slot or bore f through it for the passage of the said sliding bar D. Projecting from said body portion are two upwardly-extending arms g g' , provided at their ends with journals, through which the screw-shaft A passes. This body portion also has a transverse passage or bore h , through which extends the operating-shaft H, which is provided at its upper exposed end between the said two arms of the body portion with a beveled pinion i , engaging with the beveled wheel fixed on the said screw-shaft A. The beveled pinion i and the beveled wheel j on said operating-shaft and screw-shaft, respectively, are each provided with collars i' j' and with set-screws i^2 j^2 , whereby they are mounted thereon and by which they may be readily removed and adjusted. The lower end of the said operating-shaft is provided with a head k , having an opening, through which a sliding crank L is adapted to move. This sliding crank is provided at each end thereof with a rigid angularly-extending handle m m' , whereby it may be moved in the said slot and operated to turn the said operating-shaft. By employing an operating-shaft and crank of this construction it will be seen that the device may be operated without inconvenience close to the ground, so that the meeting ends of the lowermost strands of the wire fence may be operated upon quickly as well as the upper strands thereof.

Fig. 1 shows my wire-tightening device applied to the meeting ends of the wire strands,

the said ends being designated by the letters $o' o^2$. In the present instance the end o' is formed with a loop, with which the other end o^2 is to be engaged; but this is shown as only 5 one manner of connecting the said meeting ends and any other manner of connection may be adopted.

The clamping-blocks are each formed of two jaws $p p'$, the latter being loose, and a 10 screw-bolt r is passed through said jaws, and a hand-nut or clamping-lever p^2 is provided, whereby the same may be adjusted relative to each other to engage or disengage the wire strands. A washer q surrounds the said bolt, 15 and a key or plug q' is inserted through the jaw p' and said washer to prevent the said parts from turning when the clamping-bolt is adjusted to maintain the two clamp-jaws closed. The said washer is provided with 20 ridges q^2 , which coact with corresponding depressions on the clamping-jaw p to hold the wire tightly clamped between them, so that it cannot possibly slip while it is held under tension. The specific form of clamp herein 25 described is not essential; but any other form of clamping device may be employed for the purpose. A rib s on the jaw p prevents the screw-bolt from turning all around.

The operation is as follows: The two terminal ends $o' o^2$ are drawn primarily as tight as possible by hand, and then the two clamping-blocks $B B'$ are applied thereto. The operating-shaft H is then turned by means of the crank L , so as to cause the shaft to revolve through the action of the two beveled gears $i j$ in order to cause the said two clamping-blocks to move on the said shaft toward each other and toward the operating mechanism at the center thereof. By this operation the two terminal ends of the wire strands are drawn taut, and while taut said ends are connected in any suitable manner to maintain the wire in such position.

My invention provides a simple and effective form of device which may be easily and quickly applied to the wire and as readily removed therefrom.

By the construction of the operating mechanism herein described the terminal ends of 50 the wire cannot possibly slip, and a sufficient tension is exerted thereon to bring the same together.

Having thus described my invention, what

I claim as new, and desire to secure by Letters Patent, is—

1. The combination in a wire-fence tightener, of two blocks provided with clamping portions adapted to engage the terminal ends of the wire strands, a screw-shaft having its end passed through said blocks, a sliding bar 60 parallel to said shaft and on which the said blocks slide, and a shielding-bar applied upon the exposed ends of the said sliding bar and screw-shaft to prevent the bending of the latter, substantially as described. 65

2. In a wire-fence tightener, the combination of a shaft having its ends reversely screw-threaded, a sliding bar arranged below and parallel with the said shaft, two clamping-blocks each provided with a slot through which the said sliding bar passes and with a threaded opening adapted to engage the threaded end of the screw-shaft, operating mechanism interposed between the said two blocks, a body having a longitudinal bore 75 through which the said sliding bar passes, and a transverse bore through which the operating-shaft extends, a beveled gear upon said screw-shaft, a pinion carried by the said operating-shaft to engage said beveled gear, 80 and a crank for operating the said operating-shaft, substantially as described. 70

3. In a wire-fence tightener, the combination of a shaft having its ends reversely screw-threaded and provided intermediate of its 85 length with a gear-wheel, a sliding bar arranged below and parallel with said shaft, a clamping-block arranged upon each end of the sliding bar and provided with a threaded aperture to engage said threaded ends of the 90 screw-shaft, a head fixed upon the said sliding bar and provided with two upwardly-extending arms having journals in which the said screw-shaft is mounted, an operating-shaft extending through the said head provided with a pinion engaging with the said gear on the screw-shaft, and a crank on the threaded end of the said operating-shaft, substantially as described. 95

In testimony whereof I have signed this 100 specification in the presence of two subscribing witnesses.

JAMES NICHOLAS YOUNG.
